(57) **ABSTRACT**

A display device according to the present invention includes: an organic EL element; an electrostatic holding capacitor; a drive transistor having a gate connected to one electrode of an electrostatic holding capacitor and a source connected to an anode of the organic EL element; another electrostatic holding capacitor having an electrode connected to the other electrode of the one electrostatic holding capacitor; a negative power supply line which determines a potential of a cathode of the organic EL element; and a scanning line drive circuit which controls switching transistors. In a display period, the entire display area of a display unit is caused to start generating photons at once. In a non-display period, the entire display area of the display unit is caused to stop generating photons at once, and the drive transistor is reset.

STEREOSCOPIC DISPLAY DEVICE

CROSS REFERENCE TO RELATED APPLICATION

This is a continuation application of PCT application No. PCT/JP2011/004512 filed on Aug. 9, 2011, designating the United States of America.

BACKGROUND OF THE INVENTION

(1) Field of the Invention

The present invention relates to display devices, and particularly to a display device using current-driven luminescence elements.

(2) Description of the Related Art

Display devices using organic electroluminescence (EL) elements are well-known as display devices using current-driven luminescence elements. An organic EL display device using such self-luminous organic EL elements does not require backlights necessary in a liquid crystal display device and is most suitable for increasing device thinness. Furthermore, since viewing angle of such an organic EL display is not limited, practical application as a next-generation display device is expected. Furthermore, the organic EL elements used in the organic EL display device are different from liquid crystal cells, which are controlled according to voltage applied thereto, in that the luminance of the respective luminescence elements is controlled according to the amount of current flowing thereto.

In the organic EL display device, the organic EL elements included in the pixels are normally arranged in rows and columns. An organic EL display is called a passive-matrix organic EL display, in which organic EL elements are provided at crosspoints of row electrodes (scanning lines) and column electrodes (data lines) and voltages corresponding to data signals are applied between selected row electrodes and the column electrodes to drive the organic EL elements.

On the other hand, in an organic EL display device referred to as an active-matrix organic EL display device, a switching thin film transistor (TFT) is provided in each crosspoint between scanning lines and data lines, the gate of a drive element is connected to the switching TFT, the switching TFT is turned ON through a selected scanning line so as to input a data signal from a signal line to the drive element, and the organic EL elements are driven by the drive element.

Unlike in the passive-matrix organic EL display device in which, only during the period when each of the row electrodes (scanning lines) is selected, does the organic EL element connected to the selected row electrode generate photons, in the active-matrix organic EL display device, it is possible to cause the organic EL element to generate photons until a subsequent scan (selection), and thus increase in the number of scanning lines does not cause reduction in display luminance. Therefore, the active-matrix organic EL display device can be driven at a low voltage and thus allows for reduced power consumption.

For example, International Publication No. 2010/041426 (Patent Reference 1) discloses a circuit configuration of a pixel unit in an active-matrix organic EL display device and a method of driving the display device.

SUMMARY OF THE INVENTION

However, as described below, there is a problem with stereoscopic (3D) display using the pixel circuit disclosed in Patent Reference 1.

2

FIG. 12 shows a case of normal display (2D display) by line-sequential driving using the pixel circuit according to Patent Reference 1. FIG. 13 is a diagram for describing a problem in the case of stereoscopic (3D) display by line-sequential driving using the same pixel circuit. In FIG. 12 and FIG. 13, the vertical axis represents a position in a screen where the display device displays an image, and the horizontal axis represents time. Here, the following description is based on the premise that a stereoscopic image is shown to a viewer using a method in which the display device displays a stereoscopic image by showing an image for one eye and an image for the other eye including parallax for stereoscopic viewing alternately (sequentially) and a left-eye shutter and a right-eye shutter of a glass unit are alternately closed.

10 In the case of normal display (2D display) by line-sequential driving using the pixel circuit according to Patent Reference 1, the display device has a non-photon-generating period which sequentially starts with from the top to the bottom of the screen within a frame period as shown in FIG. 12. The 15 pixel circuit according to Patent Reference 1 has such a resetting period because the pixels in the resetting period cannot generate photons such that the resetting period is anything but a non-photon-generating period, even though providing such a resetting period is favorable for preventing an afterimage due to change in electric characteristics of a drive transistor.

20 On the other hand, in the case of stereoscopic (3D) display by line-sequential driving using the pixel circuit according to Patent Reference 1, the display device has a non-photon-generating period which sequentially starts with from the top to the bottom of the screen within a frame period in a similar way as shown in (a) in FIG. 13. Here, in order to show a stereoscopic (3D) image, a left-eye shutter and a right-eye shutter of a glass unit are alternately closed as shown in (b) in FIG. 13 so that a viewer can view a stereoscopic image.

25 30 35 However, in the case where the left-eye shutter and the right-eye shutter of the glass unit are alternately closed so that the viewer can view a stereoscopic image, a display period, during which the viewer views a stereoscopic image, lasts only for the display period as shown in (b) in FIG. 13. In other words, the viewer can view an image with both eyes for a short time compared to the case of normal display (2D display) because the viewer views the image through the glass unit. As a result, luminance to be perceived through the glass unit is very low.

40 45 50 The present invention is conceived in view of the above-described circumstances and has an object of providing a display device in which simple pixel circuitry prevents decrease in luminance and occurrence of an afterimage due to change in electric characteristics of a drive transistor are prevented during stereoscopic display operation.

55 60 65 In order to achieve the object, the display device according to an aspect of the present invention sequentially displays a right-eye image and a left-eye image so that a viewer can view a stereoscopic image through a pair of glasses which allows the viewer to sequentially view the right-eye image and the left-eye image, and the display device includes: a display unit configured to sequentially display the right-eye image and the left-eye image; and a driver unit configured to drive the display unit, wherein the display unit includes: a plurality of pixels arranged in rows and columns; a scanning line provided for each of the rows; a control line provided for each of the rows; a data line provided for each of the columns; and a first power supply line and a second power supply line for supplying power to the pixels, each of the pixels includes: a luminescence element having electrodes one of which is connected to the second power supply line; a drive transistor having a source electrode connected to the luminescence

element and a drain electrode connected to the first power supply line; a first capacitor having electrodes one of which is connected to a gate electrode of the drive transistor; a first switching transistor which has a gate electrode connected to the scanning line and switches conduction and non-conduction between the gate electrode of the drive transistor and a first reference potential line which provides a predetermined reference potential; a second switching transistor which has a gate electrode connected to the scanning line and switches conduction and non-conduction between the data line and the other of the electrodes of the first capacitor; a third switching transistor which has a gate electrode connected to the control line and switches conduction and non-conduction between the other of the electrodes of the first capacitor and the source electrode of the drive transistor; and a second capacitor having electrodes one of which is connected to the other of the electrodes of the first capacitor and the other of which is connected to a second reference potential line which provides a predetermined reference potential, and cause conduction of the first switching transistor through the scanning line in each of all the pixels of the display unit at a same time to apply the predetermined reference potential to the gate electrode of the drive transistor in the pixel, and thereby stop photon generation of all of the pixels at a same time so that a non-display period is started; cause conduction of the third switching transistor through the control line in each of all the pixels of the display unit at a same time to apply a signal voltage held by the first capacitor between the gate electrode and the source electrode of the drive transistor in the pixel, and thereby start photon generation of all of the pixels at a same time so that a display period is started; and drive the display unit so as to alternate the non-display period and the display period so that the right-eye image and the left-eye image are sequentially displayed.

According to the present invention, a display device can be provided in which decrease in luminance and occurrence of an afterimage due to change in electric characteristics of a drive transistor are prevented during stereoscopic display operation with a simple pixel circuit.

FURTHER INFORMATION ABOUT TECHNICAL BACKGROUND TO THIS APPLICATION

The disclosure of PCT application No. PCT/JP2011/004512 filed on Aug. 9, 2011, including specification, drawings and claims is incorporated herein by reference in its entirety.

BRIEF DESCRIPTION OF THE DRAWINGS

These and other objects, advantages, and features of the invention will become apparent from the following description thereof taken in conjunction with the accompanying drawings that illustrate a specific embodiment of the invention. In the Drawings:

FIG. 1 is a schematic diagram showing a configuration of a display device in the present embodiment;

FIG. 2 is a block diagram showing a configuration of the display device for stereoscopic display according to the present embodiment;

FIG. 3 is a diagram showing a circuitry configuration of a pixel of a display unit according to the embodiment of the present invention, and connection of the pixel with peripheral circuitry thereof;

FIG. 4A shows an example of an operation timing chart for the display device according to the embodiment of the present invention;

FIG. 4B shows another example of an operation timing chart for the display device according to the embodiment of the present invention;

FIG. 5 shows an example of an operation timing chart for control of a pixel included in the display unit according to the embodiment of the present invention;

FIG. 6A is a diagram for explaining the operation timing chart for control of a pixel included in the display unit according to the embodiment of the present invention;

FIG. 6B is a diagram for explaining the operation timing chart for control of a pixel included in the display unit according to the embodiment of the present invention;

FIG. 6C is a diagram for explaining the operation timing chart for control of a pixel included in the display unit according to the embodiment of the present invention;

FIG. 6D is a diagram for explaining the operation timing chart for control of a pixel included in the display unit according to the embodiment of the present invention;

FIG. 6E is a diagram for explaining the operation timing chart for control of a pixel included in the display unit according to the embodiment of the present invention;

FIG. 6F is a diagram for explaining the operation timing chart for control of a pixel included in the display unit according to the embodiment of the present invention;

FIG. 6G is a diagram for explaining the operation timing chart for control of a pixel included in the display unit according to the embodiment of the present invention;

FIG. 6H is a diagram for explaining the operation timing chart for control of a pixel included in the display unit according to the embodiment of the present invention;

FIG. 6I is a diagram for explaining the operation timing chart for control of a pixel included in the display unit according to the embodiment of the present invention;

FIG. 6J is a diagram for explaining the operation timing chart for control of a pixel included in the display unit according to the embodiment of the present invention;

FIG. 6K is a diagram for explaining the operation timing chart for control of a pixel included in the display unit according to the embodiment of the present invention;

FIG. 6L is a diagram for explaining the operation timing chart for control of a pixel included in the display unit according to the embodiment of the present invention;

FIG. 6M is a diagram for explaining the operation timing chart for control of a pixel included in the display unit according to the embodiment of the present invention;

FIG. 6N is a diagram for explaining the operation timing chart for control of a pixel included in the display unit according to the embodiment of the present invention;

FIG. 7 is a characteristics chart showing change in threshold voltage due to charges accumulated in a drive transistor;

FIG. 8 schematically shows the charges accumulated in the drive transistor;

FIG. 9 schematically shows an effect of resetting that the charges accumulated in the drive transistor are cleared;

FIG. 10 is a diagram for describing effects of the display device according to the present invention;

FIG. 11 is an outline view of a flat-panel TV in which the display device in the present invention is built into;

FIG. 12 is a diagram for describing a normal display (2D display); and

FIG. 13 is a diagram for describing a problem in the case of stereoscopic (3D) display.

DESCRIPTION OF THE PREFERRED EMBODIMENT

A display device according to an aspect of the present invention sequentially displays a right-eye image and a left-

eye image so that a viewer can view a stereoscopic image through a pair of glasses which allows the viewer to sequentially view the right-eye image and the left-eye image, and the display device includes: a display unit configured to sequentially display the right-eye image and the left-eye image; and a driver unit configured to drive the display unit, wherein the display unit includes: a plurality of pixels arranged in rows and columns; >a scanning line provided for each of the rows; a control line provided for each of the rows; a data line provided for each of the columns; and a first power supply line and a second power supply line for supplying power to the pixels, each of the pixels includes: a luminescence element having electrodes one of which is connected to the second power supply line; a drive transistor having a source electrode connected to the luminescence element and a drain electrode connected to the first power supply line; a first capacitor having electrodes one of which is connected to a gate electrode of the drive transistor; a first switching transistor which has a gate electrode connected to the scanning line and switches conduction and non-conduction between the gate electrode of the drive transistor and a first reference potential line which provides a predetermined reference potential; a second switching transistor which has a gate electrode connected to the scanning line and switches conduction and non-conduction between the data line and the other of the electrodes of the first capacitor; a third switching transistor which has a gate electrode connected to the control line and switches conduction and non-conduction between the other of the electrodes of the first capacitor and the source electrode of the drive transistor; and a second capacitor having electrodes one of which is connected to the other of the electrodes of the first capacitor and the other of which is connected to a second reference potential line which provides a predetermined reference potential, and cause conduction of the first switching transistor through the scanning line in each of all the pixels of the display unit at a same time to apply the predetermined reference potential to the gate electrode of the drive transistor in the pixel, and thereby stop photon generation of all of the pixels at a same time so that a non-display period is started; cause conduction of the third switching transistor through the control line in each of all the pixels of the display unit at a same time to apply a signal voltage held by the first capacitor between the gate electrode and the source electrode of the drive transistor in the pixel, and thereby start photon generation of all of the pixels at a same time so that a display period is started; and drive the display unit so as to alternate the non-display period and the display period so that the right-eye image and the left-eye image are sequentially displayed.

According to the present aspect, in a display device for stereoscopic (3D) display, simple pixel circuitry prevents decrease in luminance and occurrence of an afterimage due to change in electric characteristics of a drive transistor are prevented during stereoscopic display operation.

Furthermore, the non-display period includes a signal voltage writing period in which, in each of all the pixels, the first capacitor is caused to hold a signal voltage while the third switching transistor is non-conductive, and in the signal voltage writing period, the driver unit is configured to cause conduction of the first switching transistor and conduction of the second switching transistor in each of the pixels in each of the rows through the scanning line provided for the row, and cause the first capacitor in each of the pixels to hold a signal voltage transmitted from the data line provided for one of the columns which includes the pixel, so that the first capacitor of each of all the pixels is caused to hold the signal voltage.

Furthermore, the non-display period may include a resetting period in which the drive transistor in each of all the pixels of the display unit is initialized, and the resetting period may be started by the driver unit, in each of all the pixels, 5 causing non-conduction of the third switching transistor through the control line and causing conduction of the first switching transistor through the scanning line to apply a constant potential of the second power supply line to the source electrode of the drive transistor through the luminescence element and apply the predetermined reference potential to the gate electrode of the drive transistor, and terminated by the driver unit, in each of all the pixels, causing conduction of the third switching transistor through the control line to apply the signal voltage held by the first capacitor between the gate electrode and the source electrode of the drive transistor.

Furthermore, the non-display period may include a resetting period in which the drive transistor in each of all the pixels of the display unit is initialized, and the resetting period may be started by the driver unit applying a reset voltage to 10 the data line and causing conduction of the first switching transistor and conduction of the second switching transistor through the scanning line to apply the reset voltage to the source electrode of the drive transistor and apply the predetermined reference potential to the gate electrode of the drive transistor, and terminated by the driver unit causing conduction of the third switching transistor through the control line to apply the signal voltage held by the first capacitor between the gate electrode and the source electrode of the drive transistor.

Furthermore, the signal voltage writing period may be controlled by the driver unit so that the signal voltage writing period overlaps the resetting period at least in part.

Furthermore, the signal voltage writing period may be controlled by the driver unit so that the signal voltage writing period is included in the resetting period.

Furthermore, the resetting period may have a duration longer than or equal to 20% of a total duration of the display period and the non-display period.

A preferred embodiment of the present invention is hereinafter described on the basis of the drawings. Elements which are common or equivalent among all the drawings are hereinafter denoted by the same symbol, and thus a description thereof is omitted.

Embodiment

An embodiment of the present invention shall be described below with reference to the drawings.

FIG. 1 is a schematic diagram showing a configuration of a 50 display device in the present embodiment. FIG. 2 is a block diagram showing a configuration of the display device according to the present embodiment. FIG. 3 is a diagram which shows a circuitry configuration of a pixel of a display unit according to the embodiment of the present invention, 55 and connection of the pixel with peripheral circuitry thereof. It should be noted that FIG. 3 shows a circuitry configuration of one of pixels 10 and connection of the pixel 10 with peripheral circuitry thereof.

A display device 1 is used in combination with an emitter 60 1A and shutter glasses 1B as shown in FIG. 1. The emitter 1A is a transmitter to be used for synchronization of the display device 1 and the shutter glasses 1B. The shutter glasses 1B is a pair of glasses which is used by a viewer and has shutters that allow the viewer to have a stereoscopic (three-dimensional) view by sequentially showing the viewer a right-eye image and a left-eye image displayed on a display unit 6 of the display device 1.

The display device 1 includes a control circuit 2, a scanning line drive circuit 4, a signal line drive circuit 5, the display unit 6, an image signal processing circuit 7, a glasses control circuit 8, and a power supply circuit 9 as shown in FIG. 2.

The image signal processing circuit 7 receives an image signal and provides the control circuit 2 with a control signal to cause the pixels 10 included in the display unit 6 to generate photons, that is, a control signal to cause the display unit 6 to display images (a left-eye image and a right-eye image) according to the image signal. The image signal processing circuit 7 also provides the glasses control circuit 8 with a right-left timing signal together with a synchronization signal according to the image signal. Here, the control signal provided to the control circuit 2 is matched with the synchronization signal by the image signal processing circuit 7.

The glasses control circuit 8 generates a glasses control signal according to the synchronization signal and right-left timing signal provided from the image signal processing circuit 7, and provides the glasses control signal to the emitter 1A. The glasses control signal is a signal which allows the viewer to sequentially view a right-eye image and a left-eye image through the shutter glasses 1B.

Specifically, the glasses control circuit 8 generates a glasses control signal so that the right shutter and left shutter of the shutter glasses 1B open and close according to the synchronization signal and the right-left timing signal. For example, the glasses control circuit 8 generates a glasses control signal so that one of the right shutter and left shutter of the shutter glasses 1B opens and the other closes according to the synchronization signal and the right-left timing signal.

The control circuit 2 controls the scanning line drive circuit 4 and the signal line drive circuit 5 according to the control signal provided from the image signal processing circuit 7 to drive the display unit 6. The control circuit 2 drives the display unit 6 so that the display unit 6 sequentially displays a right-eye image and a left-eye image, alternating a non-display period and a display period. Specifically, the control circuit 2 provides the control by providing the scanning line drive circuit 4 with a scanning signal and the signal line drive circuit 5 with an image signal (data of a right-eye image and data of a left-eye image) so that the display unit 6 sequentially (alternately) displays a right-eye image and a left-eye image.

The power supply circuit 9 supplies power to the display unit 6. Specifically, the power supply circuit 9 supplies a positive power supply voltage VDD and a negative power supply voltage VEE to the display unit 6. Here, the power supply circuit 9 may include a power supply control circuit.

The display unit 6, which corresponds to a display unit in the present invention, sequentially displays a right-eye image and a left-eye image. Specifically, driven (controlled) by the control circuit 2, the display unit 6 sequentially displays images, that is, an image for the right eye of the viewer and an image for the left eye of the viewer, according to an image signal input from an external source to the display device 1.

More specifically, the display unit 6 includes the pixels 10 arranged in rows and columns, scanning lines 17 and scanning lines 18 provided for the respective rows of the pixels 10, signal lines 16 provided for the respective columns of the pixels 10, a positive power supply line 21 and a negative power supply line 22 for power supply to the respective pixels 10.

The scanning line drive circuit 4 is controlled by the control circuit 2. The scanning line drive circuit 4 is connected to the scanning line 17 and the scanning line 18 as shown in FIG. 3, and outputs scanning signals to the scanning line 17 and the scanning line 18 so as to control conductivity of a switching

transistor 11, a switching transistor 12, and a switching transistor 19 included in each of the pixels 10.

The signal line drive circuit 5 drives the display unit 6 under control of the control circuit 2. Specifically, the signal line drive circuit 5 is a drive circuit connected to the signal line 16 as shown in FIG. 3 and outputs a signal voltage according to an image signal to the pixel 10 under control of the control circuit 2.

The pixel 10 includes the switching transistors 11, 12, and 19, electrostatic holding capacitors 13 and 23, a drive transistor 14, an organic EL element 15, the signal line 16, the scanning lines 17 and 18, reference power supply lines 20 and 24, the positive power supply line 21, and the negative power supply line 22 as shown in FIG. 3. The peripheral circuitry includes the scanning line drive circuit 4 and the signal line drive circuit 5.

The switching transistor 11, which is an example of a second switching transistor in the present invention, has a gate connected to the scanning line 17 and switches conduction and non-conduction between the signal line 16 and an electrode 132, which is one of the electrodes of the electrostatic holding capacitor 13. Specifically, the switching transistor 11 is a second switching transistor having a gate connected to the scanning line 17, and a source and a drain one of which is connected to the signal line 16 and the other of which is connected to the electrode 132 of the electrostatic holding capacitor 13. The switching transistor 11 controls conductivity between the signal line 16 and the electrode 132 of the electrostatic holding capacitor 13 so that the switching transistor 11 controls the timing with which a signal voltage of the signal line 16 is applied to the electrode 132 of the electrostatic holding capacitor 13, and determines a voltage held between the electrodes of the electrostatic holding capacitor 13.

The switching transistor 12, which is an example of a first switching transistor in the present invention, has a gate connected to the scanning line 17 and switches conduction and non-conduction between the gate of the drive transistor 14 and the reference power supply line 20 which supplies a predetermined reference potential VREF1. Specifically, the switching transistor 12 is the first switching transistor having a gate connected to the scanning line 17 and a source and a drain one of which is connected to the reference power supply line 20 and the other of which is connected to the gate of the drive transistor 14. The switching transistor 12 determines timing with which the reference voltage VREF1 of the reference power supply line 20 is applied to the gate of the drive transistor 14. The switching transistors 11 and 12 are, for example, N-type thin film transistors (N-type TFT) but are alternatively P-type thin film transistors (P-type TFT).

The electrostatic holding capacitor 13, which is an example of a first capacitor in the present invention, has electrodes one of which is an electrode 131 connected to the gate of the drive transistor. Specifically, the electrostatic holding capacitor 13 is a first capacitor having electrodes one of which is the electrode 131 connected to the gate of the drive transistor 14, and the other of which is the electrode 132 connected to the source of the drive transistor 14 via the switching transistor 19. The electrostatic holding capacitor 13 holds a voltage corresponding to a signal voltage provided from the signal line 16. For example, the electrostatic holding capacitor 13 stabilizes a gate-source electrode potential of the drive transistor 14 after the switching transistors 11 and 12 turn OFF (non-conductive) and the switching transistor 19 turns ON (conductive), and thereby stabilizes current provided from the drive transistor 14 to the organic EL element 15.

The electrostatic holding capacitor **23**, which is an example of a second capacitor in the present invention, has electrodes one of which is an electrode **231** connected to the electrode **132** of the electrostatic holding capacitor **132**, and the other of which is an electrode **232** connected to the reference power supply line **24** which provides a predetermined reference potential. Specifically, the electrostatic holding capacitor **23** is a second capacitor having electrodes one of which is an electrode **231** connected to the electrode **132** of the electrostatic holding capacitor **13**, and the other of which is an electrode **232** connected to the reference power supply line **24**, which is the second reference potential line. With the electrode **232** connected to a fixed reference voltage VREF2 of the reference power supply line **24**, the electrostatic holding capacitor **23** reduces change in the potential VREF1 held at the first electrode **131** of the electrostatic holding capacitor **13** by the electrostatic holding capacitor **13** and the electrostatic holding capacitor **23**, even after the switching transistor **11** and the switching transistor **12** turn from ON (conductive) to OFF (non-conductive). In other words, the electrostatic holding capacitor **23** stabilizes the voltage applied to the gate electrode of the drive transistor **14** at VREF1 even when the switching transistor **11** and the switching transistor **12** turn OFF (non-conductive).

The drive transistor **14**, which is an example of the drive transistor in the present invention, has a source connected to the organic EL element **15** and a drain connected to the positive power supply line **21**. Specifically, the drive transistor **14** is a drive transistor having a drain connected to the positive power supply line **21**, which is the first power supply line, and a source connected to the anode of the organic EL element **15**. The drive transistor **14** converts a voltage corresponding to a signal voltage applied between the gate and the source to a drain current corresponding to the signal voltage. Subsequently, the drive transistor **14** supplies the drain current, as a signal current, to the organic EL element **15**. The drive transistor **14** is, for example, an N-type thin film transistor (N-type TFT). The drive transistor **14** may include a semiconductor layer including an amorphous silicon film or a crystalline silicon layer crystallized by laser-annealing an amorphous silicon film, or may include a semiconductor layer formed of an oxide of an alloy including a material such as In or Zn.

The organic EL element **15**, which is an example of a luminescence element in the present invention, has an electrode (cathode) connected to the negative power supply line **22**. Specifically, the organic EL element **15** is a luminescence element having a cathode connected to the negative power supply line **22**, which is a second power supply line. The signal current under control of the drive transistor **14** flows into the organic EL element **15**, and the organic EL element **15** thereby generates photons.

The switching transistor **19**, which is an example of a third switching transistor in the present invention, has a gate connected to the scanning line **18** and switches conduction and non-conduction between the electrode **132** of the electrostatic holding capacitor **13** and the source of the drive transistor **14**. Specifically, the switching transistor **19** is a third switching transistor having a gate connected to the scanning line **18**, and a source and a drain one of which is connected to the source of the drive transistor **14** and the other of which is connected to the electrode **132** of the electrostatic holding capacitor **13**. The switching transistor **19** determines timing with which the organic EL element **15** starts generating photons, by applying a potential held by the electrostatic holding capacitor **13** between the gate electrode and the source electrode of the drive transistor **14**. The switching transistor **19** is, for

example, an N-type thin film transistor (N-type TFT) but is alternatively a P-type thin film transistor (P-type TFT).

The signal line **16**, which is an example of a data line in the present invention, is provided for each of the columns of the pixels **10**. Specifically, the signal line **16** is connected to the signal line drive circuit **5** and to the respective pixels **10** included in the pixel column, and supplies signal voltage which determines luminescence intensity.

The scanning line **17**, which is an example of a scanning line in the present invention, is provided for each of the rows of the pixels **10**. Specifically, the scanning line **17** is connected to the scanning line drive circuit **4**, and is connected to the respective pixels **10** included in the pixel row. With this, the scanning line **17** determines timing with which the signal voltage is written in the respective pixels **10** included in the pixel row, and determines, by applying the reference voltage VREF1 to the gate of the drive transistor **14** included in each of the pixels **10**, timing with which the organic EL element **15** stop generating photons.

The scanning line **18**, which is an example of a control line in the present invention, is provided for each of the rows of the pixels **10**. Specifically, the scanning line **18** is connected to the scanning line drive circuit **4** and transfers the potential of the electrode **132** of the electrostatic holding capacitor **13** to the source of the drive transistor **14**. With this, the scanning line **18** determines timing with which the organic EL element **15** starts generating photons, by applying a luminance signal voltage held between the electrodes of the electrostatic holding capacitor **13** between the gate electrode and the source electrode of the drive transistor **14**.

The display device **1** thus includes as many the scanning lines **17** as the rows of the pixels and as many the scanning lines **18** as the rows of the pixels.

The reference power supply line **20**, which is an example of a first reference potential line in the present invention, provides a predetermined reference potential. Specifically, the reference power supply line **20** is connected to the electrode **131** of the electrostatic holding capacitor **13** and provides the reference voltage VREF1, which determines a voltage value of the electrode **131** of the electrostatic holding capacitor **13**. The VREF1 is set at a voltage at which the drive transistor **14** is OFF.

The reference power supply line **24**, which is an example of a second reference potential line in the present invention, provides a predetermined reference potential. Specifically, the reference power supply line **24** is connected to the electrode **232** of the electrostatic holding capacitor **23** and provides the reference voltage VREF2, which determines a voltage value of the electrode **232** of the electrostatic holding capacitor **23**. The reference power supply line **24** is required to stabilize voltage of the gate electrode of the drive transistor **14** only from immediately before when the scanning line **17** causes conduction of the switching transistor **11** and conduction of the switching transistor **12** until immediately before when the scanning line **18** causes conduction of the switching transistor **19**. For example, the reference power supply line **24** may be supplied with power from an independent source or from the positive power supply line **21**, the negative power supply line **22**, the reference power supply line **20**, or the scanning line **18** of the respective pixels **10**.

The positive power supply line **21**, which is an example of the first power supply line in the present invention, is connected to the drain of the drive transistor **14** and determines potential of the drain of the drive transistor **14** (VDD).

The negative power supply line **22**, which is an example of the second power supply line in the present invention, is

11

connected to the cathode of the organic EL element 15 and determines potential of the cathode of the organic EL element 15.

The display device 10 is configured as described above.

It should be noted that, although not shown in FIG. 2 or FIG. 3, the reference power supply line 20, the reference power supply line 24, and the positive power supply lines 21 and 22 are connected also to the other pixels and the power supply circuit 9. The positive power supply lines 21 and 22 are the first power supply line and the second power supply line, respectively.

Next, a method of controlling the display device 1 according to the present embodiment shall be described.

FIG. 4A is an example of an operation timing chart for the display device according to the embodiment of the present invention. In FIG. 4A, the horizontal axis represents time. The waveforms represent voltages generated in the scanning lines 17 of all the rows of the pixels 10, voltages generated in the scanning lines 18 thereof, and voltages generated in the signal lines 16 of all the columns of the pixels 10, from top to bottom. The pixels 10 of the display unit 6 are arranged in n rows and m columns. In FIG. 4A, the respective scanning lines 17 of the rows of the pixels 10 of the display unit 6 are represented as a scanning line 17(1) to a scanning line 17(n), the scanning lines 18 are represented as scanning lines 18(1 to n), and the signal lines 16 are represented as signal lines 16(1 to m). Here, a characteristic method of controlling the display device shown in FIG. 4A is as described below.

The control circuit 2 causes non-conduction of the switching transistor 19 in each of all the pixels 10 of the display unit 6 through the scanning lines 18(1 to n) (at a time point t0) and causes conduction of the switching transistor 12 in each of all the pixels 10 at the same time through the scanning line 17(1) to the scanning line 17(n) (at a time point t1) to apply a predetermined reference potential to the gate of the drive transistor 14. All the pixels 10 (organic EL elements 15) thereby stop generating photons at the same time so that a non-display period is started (from a time point t1).

The control circuit 2 also causes conduction of the switching transistor 19 in each of all the pixels 10 through the scanning lines 18(1 to n) at the same time (at a time point t6) to apply a signal voltage held by the electrostatic holding capacitor 13 between the gate and the source of the corresponding drive transistor 14. All the pixels 10 (organic EL elements 15) thereby start generating photons at the same time so that a display period is started.

The non-display period includes a resetting period in which the drive transistor 14 in each of all the pixels 10 of the display unit 6 is initialized. Typically, a non-display period is identical with a resetting period.

The resetting period is started by the control circuit 2, in each of all the pixels 10 of the display unit 6, causing non-conduction of the switching transistor 19 through the scanning lines 18(1 to n) (from the time point t0 in FIG. 4A) and causing conduction of the switching transistor 12 through the scanning line 17(1) to the scanning line 17(n) (from the time point t1 in FIG. 4A) to apply a constant potential of the negative power supply line 22 to the source of the drive transistor 14 through the organic EL element 15 and apply a predetermined reference potential to the gate of the drive transistor 14. The resetting period is terminated by the control circuit 2 causing conduction of the switching transistor 19 in each of all the pixels 10 through the scanning lines 18(1 to n) to apply a signal voltage held by the electrostatic holding capacitor 13 (Vdata) between the gate and the source of the drive transistor 14.

12

The resetting period can be controlled using another method as shown in FIG. 4B. Specifically, in each of all the pixels 10 of the display unit 6, the control circuit 2 causes conduction of the switching transistor 11 and conduction of the switching transistor 12 through the scanning lines 17(1 to n) (from a time point t1 in FIG. 4B) while keeping conduction of the switching transistor 19 through the scanning line 18(1 to n) (from a time point t0 in FIG. 4B). The resetting period may be thus started by applying a constant potential to the source of the drive transistor 14 and the anode of the organic EL element 15 from the signal line 16 through the switching transistor 19 and applying a predetermined reference potential to the gate of the drive transistor 14. With this, the switching transistor 11 and the switching transistor 12 are made non-conductive through the scanning lines 17(1 to n) at a time point t2 and the switching transistor 19 is made non-conductive through the scanning lines 18(1 to n) so that voltage of the gate of the drive transistor 14 is stabilized by the electrostatic holding capacitor 13 and the electrostatic holding capacitor 23 and potential of the source of the drive transistor 14 is stabilized by the organic EL element 15. The resetting period is terminated by the control circuit 2 causing conduction of the switching transistor 19 in each of all the pixels 10 through the scanning lines 18(1 to n) at a time point t6 to apply a signal voltage held by the electrostatic holding capacitor 13 (Vdata) between the gate and the source of the drive transistor 14.

Furthermore, the non-display period includes a writing period in which, sequentially through all the pixels 10 of the display unit 6, the electrostatic holding capacitor 13 in each of the pixels 10 is caused to hold a signal voltage while the switching transistor 19 is non-conductive.

In the writing period, the control circuit 2 sequentially causes conduction of the switching transistor 12 and conduction of the switching transistor 11 in each of the pixels 10 in each of the rows of the pixels 10 of the display unit 6 through the scanning line 17(x) provided for the row (at a time point t3), and causes the electrostatic holding capacitor 13 in the pixel 10 to hold a signal voltage transmitted from the signal line 16 provided for one of the columns which includes the pixel 10, so that the electrostatic holding capacitor 13 of each of all the pixels 10 is caused to hold the signal voltage.

Here, the control circuit 2 controls the writing period so that the writing period is included in at least part of the resetting period as shown in FIG. 4A. Typically, a writing period is included in a resetting period.

It should be noted that a writing period may be controlled using a scanning method other than the method of sequential scanning as described above, in which the switching transistor 12 and the switching transistor 11 in each of all the pixels 10 are made conductive sequentially on a row basis and the electrostatic holding capacitor 13 in each of all the pixels 10 is sequentially caused to hold a signal voltage. For example, a writing period may be controlled using a scanning method in which the order in which the electrostatic holding capacitor 13 in each of the pixels 10 is caused to hold a signal voltage may be switched on a row basis. In the case where a writing period may be controlled using the scanning method in which the order in which the electrostatic holding capacitor 13 in each of the pixels 10 is caused to hold a signal voltage may be switched on a row basis, when the order of signal voltages to be transmitted from the signal line 16 is changed so that the order of transmission of data to the signal lines 16 is changed to, for example, the third row, the fifth row, the first row, the second row, and then the fourth row in sequence, the scanning lines 17 are accordingly turned ON in a sequence of the scanning line 17(3), the scanning line 17(5), the scanning line 17(1), the scanning line 17(2), and then the scanning line

17 (4). Furthermore, the order of transmission of data to the signal lines 16 and the order in which the scanning lines 17 are turned ON may be changed frame by frame in a corresponding manner.

To put it another way, in the display device according to the present embodiment, control is performed so that each frame period includes a non-photon-generating period and a display period. The entire display unit 6 is caused to stop generating photons at once at the beginning of a non-display period and is caused to start generating photons at once at the beginning of a display period so that a right-eye image and a left-eye image are alternately displayed in sequence so as to allow a viewer to view the right-eye image and the left-eye image as a stereoscopic image through glasses for sequential viewing of the right-eye image and the left-eye image.

For example, the control circuit 2 changes the voltage levels of the signal lines 16 (1 to n) of all the pixels 10 of the display unit 6 from HIGH to LOW at the time point t0, and changes the voltage levels of the scanning line 17 (1) to the scanning line 17 (n) of all the pixels 10 of the display unit 6 from LOW to HIGH at the time point t1 so that a non-display period and a resetting period are started. Here, the resetting period is started because the change of the voltage levels of the scanning line 17 (1) to the scanning line 17 (n) from LOW to HIGH causes a constant potential to be applied to the source of the drive transistor 14 from the negative power supply line 22 through the organic EL element 15 and causes a predetermined reference potential to be applied to the gate of the drive transistor 14 such that a reverse-biased voltage is applied to the drive transistor 14 which is thereby initialized.

Next, a method of controlling the pixels 10 of the display unit 6 according to the embodiment of the present invention shall be described using one of the pixels 10 of the display unit 6 as an example.

FIG. 5 is an example of an operation timing chart for control of a pixel included in the display unit according to the embodiment of the present invention. In FIG. 5, the horizontal axis represents time. The waveforms represent voltages generated in the scanning line 17 (x), voltages generated in the scanning line 18 (x), and voltages generated in the signal line 16 of one of the pixels 10 of the display unit 6, from top to bottom.

FIG. 6A to FIG. 6N are diagrams for explaining the operation timing chart for control of a pixel included in the display unit according to the embodiment of the present invention, showing conduction in the pixel circuit. The following description is based on the premise that the voltage level of HIGH is +20V and the voltage level of LOW is -10V both for the scanning line 17 (x) and the scanning line 18 (x), but it is also possible to provide different HIGH levels or different LOW levels for the scanning line 17 and the scanning line 18 depending on electric characteristics of the switching transistors 11, 12, and 19.

First, at a time point t0, the scanning line drive circuit 4 keeps the voltage level of the scanning line 17 (1) to the scanning line 17 (n) for all the pixels 10 of the display unit 6 LOW as shown in FIG. 5, so that the switching transistors 11 and 12 remain OFF. On the other hand, the scanning line drive circuit 4 changes the voltage level of the scanning lines 18 (1 to n) for all the pixels 10 of the display unit 6 from HIGH to LOW, so that the switching transistors 19 are turned OFF. Then, there is no conduction between the source of the drive transistor 14 and the electrode 132 of the electrostatic holding capacitor 13 in each of all the pixels 10 of the display unit 6 (for example, see FIG. 6A). The time point t0 is thus immediately after the source of the drive transistor 14 and the electrode 132 of the electrostatic holding capacitor 13 are

electrically disconnected. Then, the electrode 132 of the electrostatic holding capacitor 13 holds a voltage of the anode of the organic EL element 15 (VEL1 (ON)) due to the electrostatic holding capacitor 23, and the electrostatic holding capacitor 13 keeps the gate voltage of the drive transistor 14 at the level when the switching transistor 19 is ON, so that the organic EL element 15 keeps generation of photons.

Next, at a time point t1, a non-display period of the pixel 10 and a resetting period of the drive transistor 14 are started as shown in FIG. 5 and FIG. 6B. The non-display period and the resetting period are started in all the pixels 10 of the display unit 6 in the present embodiment, one of the pixels 10 shall be described below.

Specifically, the scanning line drive circuit 4 keeps the voltage level of the scanning line 18 (x) LOW so that the switching transistor 19 remains OFF (non-conductive) as shown in FIG. 5 and FIG. 6B. The scanning line drive circuit 4 also changes the voltage level of the scanning line 17 (x) from LOW to HIGH while the switching transistor 19 is OFF (non-conductive) so that the switching transistor 12 and the switching transistor 11 are turned ON (conductive).

Specifically, at the time point t1, a reference voltage of the reference power supply line 20 (VREF1) is applied to the gate of the drive transistor 14, and a voltage equivalent to the total of the voltage of the negative power supply line 22 (VEE) and a voltage having a value larger than or equal to the absolute value of a photon-generating threshold voltage of the organic EL element 15 is applied to the source of the drive transistor 14. In addition, the reference voltage VREF1 of the reference power supply line 20 is applied to the electrode 131 of the electrostatic holding capacitor 13 so that the electrode 131 of the electrostatic holding capacitor 13 holds the reference voltage (VREF1) of the reference power supply line 20. With this, the drive transistor 14 is turned OFF.

To put it another way, at the time point t1, the switching transistor 19 is OFF (non-conductive) so that the potential of the anode of the organic EL element 15, which is equal to the source voltage of the drive transistor 14, gradually approaches the total of the voltage of the negative power supply line 22 (VEE) and a voltage having a value equal to the absolute value of the photon-generating threshold voltage of the organic EL element 15. With this, discharge of unnecessary charges accumulated in the drive transistor 14 and the organic EL element 15 during the non-display period in a previous frame (a right-eye frame in FIG. 5), that is, resetting of the drive transistor 14 is started.

At the same time, the source of the drive transistor 14 is being set to a fixed voltage corresponding to the potential of the negative power supply line 22 (VEE).

Here, the fixed voltage corresponding to the potential of the negative power supply line 22 (VEE) has a value which is, for example, the total of the value of the voltage of the negative power supply line 22 (VEE) and the absolute value of a threshold voltage at which the organic EL element 15 starts generating photons (Vth(EL)). Therefore, application of a reversed bias (constant voltage) to the drive transistor 14 is started so that $V_{GS} - V_{th(TFT)} = V_{REF1} - (VEE + V_{th(EL)}) - V_{th(TFT)} = -1 < 0$, where $VEE = 5V$, $V_{REF1} = 5V$, $V_{th(EL)} = 2V$, $V_{th(TFT)} = 1V$.

Then, the drive transistor 14 turns OFF and the source-drain current of the drive transistor 14 does not flow, so that the organic EL element 15 generates no photons. In other words, the organic EL element 15 does not generate photons at the time point t1. With this, causing conduction of the switching transistor 11 and conduction of the switching transistor 12 through the scanning line 17 while the switching transistor 19 is OFF (non-conductive) is equivalent to appli-

cation of a reversed bias (a constant voltage) between the gate and the source of the drive transistor 14, so that convergence of the source potential (resetting period) of the drive transistor 14 due to self-discharge of the organic EL element 15 is started with certainty.

Next, at a time point t2, the scanning line drive circuit 4 changes the voltage level of the scanning line 17 (x) from HIGH to LOW as shown in FIG. 5 so that the switching transistors 11 and 12 are turned OFF (non-conductive). With this, the electrode 131 of the electrostatic holding capacitor 13 and the reference power supply line 20 are electrically disconnected (non-conductive) and the electrode 132 of the electrostatic holding capacitor 13 and the signal line 16 are electrically disconnected (non-conductive) as shown in FIG. 6C. At the same time, the source of the drive transistor 14 is being set to a fixed voltage corresponding to the potential of the negative power supply line 22 (VEE).

More specifically, at the time point t2, the scanning line drive circuit 4 keeps the voltage level of the scanning line 18 (x) LOW as shown in FIG. 5 so that the switching transistor 19 remains OFF (non-conductive). The scanning line drive circuit 4 changes the voltage level of the scanning line 17 (x) from HIGH to LOW while the switching transistor 19 is OFF (non-conductive) so that the switching transistor 12 and the switching transistor 11 are turned OFF (non-conductive). It should be noted that the drive transistor 14 is being reset at this time. This is because the electrostatic holding capacitor 23 reduces change in the potential of the first electrode 231 of the electrostatic holding capacitor 23, that is, the second electrode 132 of the electrostatic holding capacitor 13 even after the switching transistor 11 and the switching transistor 12 turn from ON (conductive) to OFF (non-conductive), and the electrostatic holding capacitor 13 thereby reduces change in the potential of the first electrode 131 of the electrostatic holding capacitor 13. In other words, the electrostatic holding capacitor 13 and the electrostatic holding capacitor 23 stabilize the gate potential of the drive transistor 14 at VREF1 even after the time point t2 at which the switching transistor 12 and the switching transistor 11 turn OFF (non-conductive), so that a reversed bias (constant voltage) is continuously applied between the gate and the source of the drive transistor 14.

Next, at a time point t3, setting a data voltage in the electrode 132 of the electrostatic holding capacitor 13 (writing period) is started as shown in FIG. 5.

Specifically, the scanning line drive circuit 4 keeps the voltage level of the scanning line 18 (x) LOW so that the switching transistor 19 remains OFF (non-conductive) as shown in FIG. 5 and FIG. 6D. The scanning line drive circuit 4 changes the voltage level of the scanning line 17 (x) from LOW to HIGH while the switching transistor 19 is OFF (non-conductive) so that the switching transistor 12 and the switching transistor 11 are turned ON (conductive).

It should be noted that the drive transistor 14 is still being reset. This is because the drive transistor 14 is reset by applying a constant voltage (reversed bias) between the gate and the source of the drive transistor 14.

Specifically, at the time point t3, a reference voltage of the reference power supply line 20 (VREF1) is applied to the gate of the drive transistor 14, and a voltage equivalent to the total of the voltage of the negative power supply line 22 (VEE) and a voltage having a value smaller than or equal to the absolute value of a photon-generating threshold voltage of the organic EL element 15 is applied to the source of the drive transistor 14. In addition, the reference voltage VREF1 of the reference power supply line 20 is applied to the electrode 131 of the electrostatic holding capacitor 13 so that the electrode 131 of the electrostatic holding capacitor 13 holds the reference

voltage (VREF1) of the reference power supply line 20. The drive transistor 14 is thereby continuously being reset.

Furthermore, at the time point t3, the signal line drive circuit 5 applies the signal voltage (Vdata1) to the signal line 16 (x). Then, the voltage of the electrode 132 of the electrostatic holding capacitor 13 (voltage Vx) is set to the signal voltage (Vdata1) of the signal line 16. On the other hand, the voltage of the electrode 131 of the electrostatic holding capacitor 13 is set to the reference voltage (VREF1) of the reference power supply line 20. With this, a voltage corresponding to the potential difference between the signal voltage (Vdata) and the reference voltage (VREF1) is held by the electrostatic holding capacitor 13.

The reference voltage VREF1 is an OFF-state voltage at which the drive transistor 14 is OFF (non-conductive). The condition for turning OFF the drive transistor 14 is VREF1 VEE+Vth(EL)+Vth(TFT) where the photon-generating threshold voltage of the organic EL element 15 is Vth(EL) and the threshold voltage of the drive transistor 14 is Vth (TFT). For example, when the threshold voltage of the drive transistor 14 is 1 V and the photon-generating threshold voltage of the organic EL element 15 is 2 V in an absolute value, the voltage of the positive power supply line 21 is set at 25 V, the voltage of the negative power supply line 22 is set at 5 V, and the voltage of the reference power supply line 20 is set at 5 V.

Next, during the period from the time point t3 to a time point t4, the voltage level of the scanning line 17 (x) is HIGH as shown in FIG. 5, so that the signal voltage (Vdata1) is applied from the signal line 16 (x) to the electrode 132 of the pixel 10. The voltage of the source of the drive transistor 14 of each of the pixels 10 included in a pixel row is set at a fixed voltage corresponding to the potential of the negative power supply line 22 (VEE).

In this period, connected to the reference power supply line 20 is only capacitive load, and therefore there is no stationary current or voltage drop while the voltage level of the scanning line 17 is HIGH. The potential difference between the drain and the source of the switching transistor 12 is 0 V when charging of the electrostatic holding capacitor 13 is completed. The same occurs to the signal line 16 and the switching transistor 11. Thus, a reference potential (VREF1) and a signal voltage (Vdata) which accurately correspond to the signal voltage are written in the electrode 131 and the electrode 132 of the electrostatic holding capacitor 13, respectively.

Next, at a time point t4, the scanning line drive circuit 4 changes the voltage level of the scanning line 17 (x) from HIGH to LOW as shown in FIG. 5 so that the switching transistors 11 and 12 are turned OFF (non-conductive). With this, the electrode 131 of the electrostatic holding capacitor 13 and the reference power supply line 20 are electrically disconnected (non-conductive) and the electrode 132 of the electrostatic holding capacitor 13 and the signal line 16 are electrically disconnected (non-conductive) as shown in FIG. 6E.

More specifically, at the time point t4, the scanning line drive circuit 4 keeps the voltage level of the scanning line 18 (x) LOW as shown in FIG. 5 so that the switching transistor 19 remains OFF (non-conductive). The scanning line drive circuit 4 changes the voltage level of the scanning line 17 (x) from HIGH to LOW while the switching transistor 19 is OFF (non-conductive) so that the switching transistor 12 and the switching transistor 11 are turned OFF (non-conductive). It should be noted that resetting of the drive transistor 14 is being reset at this time. This is because, as described above, the electrostatic holding capacitor 23 and the electrostatic

holding capacitor **13** reduce change in the potential of the electrode **131** of the electrostatic holding capacitor **13** even after the switching transistor **11** and the switching transistor **12** turn from ON (conductive) to OFF (non-conductive). In other words, the electrostatic holding capacitor **13** and the electrostatic holding capacitor **23** stabilize the potential held by the electrode **131** of the electrostatic holding capacitor **13** even after the time point **t4** at which the switching transistor **12** and the switching transistor **11** turn OFF (non-conductive) again. When a resetting period of the drive transistor **14** having a sufficient duration is secured, the potential of the source of the drive transistor **14** approaches a fixed voltage ($VEE+Vth(EL)$) corresponding to the reference voltage **VREF1** all the more for the duration of resetting period, which is preferable. In the present embodiment, the resetting period lasts until a time point **t6**.

In the present embodiment, however, the potential of the source of the drive transistor **14** is close to a fixed voltage ($VEE(off)=VEE+Vth(EL)$) corresponding to the reference voltage **VREF1** at a time **t5** (for example, see FIG. 6F). Here, the fixed voltage corresponding to the reference voltage **VREF1** is a potential determined based on electric characteristics of the drive transistor **14**, electric characteristics of the organic EL element **15**, and the reference voltage **VREF1**.

Next, at a time point **t6**, a resetting period of the drive transistor **14** is terminated and a display period is started as shown in FIG. 5. Specifically, as shown in FIG. 5, keeping the voltage level of the scanning line **17** (x) LOW so that the switching transistor **11** and the switching transistor **12** remain OFF (non-conductive), the scanning line drive circuit **4** changes the voltage level of the scanning line **18** (x) from LOW to HIGH so that the switching transistor **19** is turned ON (conductive).

Then, the source of the drive transistor **14** and the electrode **132** of the electrostatic holding capacitor **13** are electrically connected as shown in FIG. 6G. On the other hand, the electrode **131** of the electrostatic holding capacitor **13** is electrically disconnected from the reference power supply line **20**, and the electrode **132** is electrically disconnected from the signal line **16**.

With this, at the time point **t6**, the electrostatic holding capacitor **13** is electrically connected to between the gate and the source of the drive transistor **14**, and the gate of the drive transistor **14** is set at a potential of the electrode **131** of the electrostatic holding capacitor **13** ($VREF1-Vdata+VEL(off)$), and the source of the drive transistor **14** is set at a potential of the electrode **132** of the electrostatic holding capacitor **13** ($VEL2(off)$). To put it another way, the potential difference between the electrode **131** and the electrode **132** of the electrostatic holding capacitor **13** ($VREF1-Vdata$) is applied between the gate electrode and the source electrode of the drive transistor **14**. Then, a current flows between the drain and the source of the drive transistor **14** according to the potential difference between the gate electrode and the source electrode of the drive transistor **14**, and thereby the organic EL element **15** starts generating photons. When the organic EL element **15** starts generating photons, the potential of the source of the drive transistor **14** changes to $VEL(ON)$. Then, the potential of the gate of the drive transistor **14** is set at a potential of the electrode **131** of the electrostatic holding capacitor **13** ($VREF1-Vdata+VEL(on)$), so that the potential difference between the electrode **131** and the electrode **132** of the electrostatic holding capacitor **13** ($VREF1-Vdata$) is continuously applied between the gate electrode and the source electrode of the drive transistor **14**. In other words, the gate potential of the drive transistor **14** changes with change in the source potential by bootstrapping, and a voltage across the

electrostatic holding capacitor **13** ($VREF1-Vdata$) is applied between the gate and the source of the drive transistor **14**, so that a signal current corresponding to the voltage ($VREF1-Vdata$) flows into the organic EL element **15**, causing the organic EL element **15** to generate photons. It should be noted that, in the present embodiment, the source potential of the drive transistor **14** changes, for example, from 7V to 10V due to conduction of the switching transistor **19**.

In the period from the time point **t6** to a time point **t7** (namely, a display period), the voltage across the electrostatic holding capacitor **13** ($VREF1-Vdata$) is continuously applied between the gate and the source, and the signal current thereby flows to cause the organic EL element **15** to keep generating photons.

The period from the time point **t0** to the time point **t7** corresponds to a left-eye frame period (a $1/2$ frame period) in which luminescence intensities of all the pixels of the display device **1** are refreshed, and the operation in the period from the time point **t0** to the time point **t7** is repeated after the time point **t7**. For example, a time point **t7** to a time point **t14** in a right-eye frame period correspond to the time point **t0** to the time point **t7**, respectively. The operation in the method of controlling the pixels of the display unit **6** from the time point **t7** to the time point **t14** shown in FIG. 5 and FIG. 6H to FIG. 6N is the same as in the period from the time point **t0** to the time point **t7**, and therefore the description thereof is omitted.

The pixels **10** of the display unit **6** are controlled as described above so that change in threshold voltage due to charges accumulated in the drive transistor **14** during the display period in the previous frame (a right-eye frame or a left-eye frame) is reduced. In other words, with the resetting period having a sufficient duration as described above, the threshold voltage of the drive transistor **14** can be stabilized. To put it another way, the electric characteristics of the drive transistor **14** at the start of generation of photons allow provision of a desired current to the organic EL element **15** after the resetting period without being affected by the previous frame (a right-eye frame or a left-eye frame).

Furthermore, the electrostatic holding capacitor **13** holds a voltage corresponding to the potential difference between the signal voltage (for example, $Vdata1$) and the reference voltage (**VREF1**), and a combined capacitance of the electrostatic holding capacitor **13** and the electrostatic holding capacitor **23** allows stable supply of the reference voltage (**VREF1**) to the gate of the drive transistor **14**, and resetting is thereby started. As such, the signal line **16** is not occupied by one cycle of luminescence production in one pixel during two operations of data writing, that is, writing for stopping photon generation and writing for photon generation. As a result, writing is necessary only once for each pixel in a row, so that two-fold writing speed is not necessary for completing writing of data in all the rows in a determined frame period. In other words, it is not necessary to lower a wiring time constant for the signal line **16** and the scanning lines **17** and **18** or to form a thick wiring film or a thick inter wiring insulation film. Accordingly, reduction in process time, increase in throughput, and cost reduction can be achieved.

It should be noted that, although one of the pixels **10** of the display unit **6** is used as an example for description of the writing period, the writing period does not start in all the pixels of the display unit **6** at once. As described above, the writing period starts in each of the pixels **10** of the display unit **6**. In other words, in the writing period, a desired signal voltage is written in each of the pixels **10** of the display unit **6** by controlling each of the scanning line **17** (1) to the scanning line **18** (**n**) of the pixel from the time point **t3** and the time point **t4** in a corresponding manner as described above.

The following describes a mechanism for stabilizing the threshold voltage of the drive transistor **14** by securing a resetting period having a sufficient duration without being affected by a previous frame (a right-eye frame or a left-eye frame) as described above.

One of the pixels **10** shall be described below as an example. First, change in threshold voltage due to charges accumulated in the drive transistor **14** in the display period of the previous frame shall be described, which is followed by a description of an effect of resetting in the display device using the method of controlling the display device according to the present embodiment.

FIG. 7 is a characteristics chart showing change in threshold voltage due to charges accumulated in a drive transistor. FIG. 8 schematically shows the charges accumulated in the drive transistor.

In FIG. 7, the vertical axis represents log values (Id) of current values, and the horizontal axis represents values of gate voltage applied to the gate.

The curve A in FIG. 7 shows the initial characteristics of the drive transistor. (a) in FIG. 8 schematically shows charges accumulated in the drive transistor having the initial characteristics (indicated by the curve A). Similarly, the curve B shows the characteristics of the drive transistor **14** when stress of voltage applied between the gate and the source (also referred to as V_{gs} stress) is low. (b) in FIG. 8 schematically shows charges accumulated in the drive transistor having the characteristics shown by the curve B. The curve C shows the characteristics of the drive transistor when the V_{gs} stress is high. (c) in FIG. 8 schematically shows charges accumulated in the drive transistor having the characteristics indicated by the curve C.

FIG. 7 and FIG. 8 show that the higher the V_{gs} stress applied to the drive transistor is, the more the accumulated charges are. FIG. 7 and FIG. 8 also show that the more the accumulated charges are (the higher the applied V_{gs} stress is), the larger the change in the threshold for the drive transistor (V_{th} shift) is. In other words, the accumulation of charges in a frame period causes the change in the voltage-current characteristics of the drive transistor.

In addition, the charges are accumulated under V_{gs} stress over a relatively long time, and clearing the accumulated charges also takes a relatively long time as it is known. Such accumulated charges are therefore insufficiently cleared in a panel in which a resetting period is not long enough. As a result, there is a problem that an afterimage occurs due to change in the electric characteristics of a drive transistor.

In contrast, a resetting period of the display device or the method of controlling the display device according to the present embodiment has such a long duration that accumulated charges can be cleared and the characteristics of the drive transistor are thereby initialized. This is schematically shown in FIG. 9. Here, FIG. 9 schematically shows the effect of resetting that the charges accumulated in the drive transistor are cleared. It should be noted that this is schematically shown in FIG. 9 using the structure shown in FIG. 8.

As shown in (a) in FIG. 9, a V_{gs} stress greater than zero is applied to the drive transistor in an initial state. Then, charges are trapped at a localized level of the gate insulation film of the drive transistor as shown in (b) in FIG. 9. Here, the V_{gs} stress greater than zero can be applied by applying, for example, 0 V to the source, 5 V to the drain, and 5 V to the gate.

After a resetting period having a sufficient duration elapses in the controlling method, the charges trapped at the localized level of the gate insulation film of the drive transistor are emitted so that the drive transistor enters a state equivalent to

the initial state as shown in (c) in FIG. 9. Here, a V_{gs} stress smaller than zero is applied to the drive transistor in the resetting period by applying, for example, 12 V to the source, 25 V to the drain, and 10 V to the gate. The charges trapped at the localized level of the gate insulation film of the drive transistor are thereby discharged.

Although the structure of the drive transistor described above is a channel-etch structure, which is described as an example, the structure of the drive transistor is not limited to this. The drive transistor may have an etching stopper structure.

As described above, according to the display device and the method of controlling the display device in the present embodiment, decrease in luminance and occurrence of an afterimage due to change in electric characteristics of a drive transistor can be prevented during stereoscopic display operation with a simple pixel circuit.

Specifically, in the display device according to the present embodiment, the entire display area of the display unit **6** is caused to start generating photons at once at the beginning of a display period, and the entire display area of the display unit **6** is caused to stop generating photons at once at the beginning of a non-display period as described above. In other words, the entire display area is caused to start generating photons or stop generating photons at once by providing control so that a writing period in which a signal voltage is written in the electrostatic holding capacitor **13** in a corresponding row out of all the pixel **10** overlaps a resetting period, which is also a non-display period in which the drive transistor **14** is initialized (reset), (or they are concurrent) at least in part. With this, a high luminescence duty cycle (luminance) can be secured during stereoscopic display operation as shown in FIG. 10. Here, FIG. 10 is a diagram for describing effects of the display device according to the present invention. For example, the non-photon-generating period after stopping generating photons at once as shown in (c) in FIG. 10 and (d) in FIG. 10 is shorter than the non-photon-generating period which starts with from the top row to the bottom row of the screen in a conventional technique as shown in (a) in FIG. 10 and (b) in FIG. 10. This is because providing the writing period within the non-display period after stopping generating photons at once eliminates the need for inserting a non-photon-generating period (black frame insertion period) at the bottom row of the screen as in the conventional technique. This is also because starting generating photons at once allows for a maximum duration of a period for opening the right and left shutters of the shutter glasses **1B**.

Furthermore, the display device according to the present embodiment includes the electrostatic holding capacitor **23** so that the potential of the gate of the drive transistor **14** is maintained even after the switching transistor **12** becomes non-conductive after the start of a resetting period. With this, the resetting period is continued. Such a configuration in which a resetting period is continued allows causing a display unit to start generating photons at once and stop generating photons the display unit at once so that a high luminescence duty cycle (luminance) can be secured during stereoscopic display operation. Here, initialization (resetting) is an operation for eliminating hysteresis of the drive transistor **14** by applying a predetermined potential to each of the gate and the source of the drive transistor **14** for a predetermined period as described above.

Furthermore, in the display device according to the present embodiment, a non-display period is also a resetting period. The resetting period therefore has a sufficient duration so that a negative effect (afterimage) due to change in electric characteristics can be reduced.

21

It is preferable that the resetting period last for 25% of a frame period (a period of a left-eye frame or a right-eye frame) or longer. In the control method described above, the resetting period is identical with the non-display period. Here, the non-display period is, for example, a period from a time point t_1 to a time point t_7 and corresponds to a period from when the switching transistor **11** and the switching transistor **12** are made conductive while the switching transistor **19** is non-conductive to when the switching transistor **19** is made conductive while the switching transistor **11** and the switching transistor **12** are non-conductive. Here, a frame period is, for example, a period from a time point t_1 to a time point t_8 and corresponds to a period from when the switching transistor **11** and the switching transistor **12** are made conductive while the switching transistor **19** is non-conductive (the time point t_1) to when the switching transistor **11** and the switching transistor **12** are next made conductive while the switching transistor **19** is non-conductive (the time point t_8). 15

A display device according to the present invention is thus provided, including simple pixel circuitry which can prevent decrease in luminance and occurrence of an afterimage due to change in electric characteristics of a drive transistor even in stereoscopic display operation. 20

Although only an exemplary embodiment of the present invention has been described in detail above, those skilled in the art will readily appreciate that many modifications are possible in the exemplary embodiment without materially departing from the novel teachings and advantages of this invention. Accordingly, all such modifications are intended to be included within the scope of this invention. 25

It should be noted that although the drive transistor **14** is an N-type transistor and the cathode of the organic EL element **15** is connected to a common power supply line in the embodiment described above, the drive transistor **14** may be a P-type transistor and the anode of the organic EL element **15** may be connected to the common power supply line such that the display device can provide the same effects as in the embodiment described above. 30

Furthermore, the present invention is not limited to what is called a shutter-glasses system as described above but is also applicable to other systems such as a polarized-glasses system (a system in which polarized glasses and active polarization plates are used) so that a stereoscopic (3D) display is achieved. 40

Furthermore, for example, the display device according to the present invention is built into a thin, flat TV as shown in FIG. 11. The thin, flat TV having the built-in display device according to the present invention is capable of high-accuracy image display reflecting a video signal. 45

INDUSTRIAL APPLICABILITY

The present invention is particularly useful in an active-type organic EL flat panel display which causes luminance to change by controlling pixel luminescence intensity according to a pixel signal current. 55

What is claimed is:

1. A display device which sequentially displays a right-eye image and a left-eye image so that a viewer can view a stereoscopic image through a pair of glasses which allows the viewer to sequentially view the right-eye image and the left-eye image, the display device comprising: 60

a display configured to sequentially display the right-eye

image and the left-eye image; and

a driver configured to drive the display, 65

wherein the display includes:

a plurality of pixels arranged in rows and columns;

22

a scanning line provided for each of the rows; a control line provided for each of the rows; a data line provided for each of the columns; and a first power supply line and a second power supply line for supplying power to the pixels, 5

each of the pixels includes:

a luminescence element having electrodes one of which is connected to the second power supply line;

a drive transistor having a source electrode connected to the luminescence element and a drain electrode connected to the first power supply line;

a first capacitor having electrodes one of which is connected to a gate electrode of the drive transistor;

a first switching transistor which has a gate electrode connected to the scanning line and switches conduction and non-conduction between the gate electrode of the drive transistor and a first reference potential line which provides a predetermined reference potential;

a second switching transistor which has a gate electrode connected to the scanning line and switches conduction and non-conduction between the data line and the other of the electrodes of the first capacitor;

a third switching transistor which has a gate electrode connected to the control line and switches conduction and non-conduction between the other of the electrodes of the first capacitor and the source electrode of the drive transistor; and

a second capacitor having electrodes one of which is connected to the other of the electrodes of the first capacitor and the other of which is connected to a second reference potential line which provides a predetermined reference potential,

the driver is configured to:

cause conduction of the first switching transistor through the scanning line in each of all the pixels of the display at a same time to apply the predetermined reference potential to the gate electrode of the drive transistor in the pixel, and thereby stop photon generation of all of the pixels at a same time so that a non-display period is started;

cause conduction of the third switching transistor through the control line in each of all the pixels of the display at a same time to apply a signal voltage held by the first capacitor between the gate electrode and the source electrode of the drive transistor in the pixel, and thereby start photon generation of all of the pixels at a same time so that a display period is started; and drive the display so as to alternate the non-display period and the display period so that the right-eye image and the left-eye image are sequentially displayed,

the non-display period includes a resetting period in which the drive transistor in each of all the pixels of the display is initialized, and

the resetting period is:

started by the driver applying a reset voltage to the data line, causing conduction of the first switching transistor and conduction of the second switching transistor through the scanning line, and causing conduction of the third switching transistor through the control line to apply the reset voltage to the source electrode of the drive transistor and apply the predetermined reference potential to the gate electrode of the drive transistor; and

terminated by the driver causing conduction of the third switching transistor through the control line to apply the signal voltage held by the first capacitor between

23

the gate electrode and the source electrode of the drive transistor, the termination being performed after a signal voltage writing period in which, in each of all the pixels, the first capacitor is caused to hold a signal voltage.

2. The display device according to claim 1, wherein the signal voltage writing period is included in the resetting period, and

in the signal voltage writing period,

the driver is configured to cause, while the third switching transistor in each of all the pixels is non-conductive, conduction of the first switching transistor and conduction of the second switching transistor in each of the pixels in each of the rows through the scanning line provided for the row, and cause the first capacitor in each of the pixels to hold a signal voltage transmitted from the data line provided for one of the columns which includes the pixel, so that the first capacitor of each of all the pixels is caused to hold the signal voltage.

3. The display device according to claim 1, wherein the resetting period has a duration longer than or equal to 20% of a total duration of the display period and the non-display period.

4. A display device which sequentially displays a right-eye image and a left-eye image so that a viewer can view a stereoscopic image through a pair of glasses which allows the viewer to sequentially view the right-eye image and the left-eye image, the display device comprising:

a display configured to sequentially display the right-eye image and the left-eye image; and
a driver configured to drive the display, wherein the display includes:

a plurality of pixels arranged in rows and columns; a scanning line provided for each of the rows; a control line provided for each of the rows; a data line provided for each of the columns; and a first power supply line and a second power supply line for supplying power to the pixels, each of the pixels includes:

a luminescence element having electrodes one of which is connected to the second power supply line;

a drive transistor having a source electrode connected to the luminescence element and a drain electrode connected to the first power supply line;

a first capacitor having electrodes one of which is connected to a gate electrode of the drive transistor;

a first switching transistor which has a gate electrode connected to the scanning line and switches conduction and non-conduction between the gate electrode of the drive transistor and a first reference potential line which provides a predetermined reference potential;

a second switching transistor which has a gate electrode connected to the scanning line and switches conduction and non-conduction between the data line and the other of the electrodes of the first capacitor;

a third switching transistor which has a gate electrode connected to the control line and switches conduction and non-conduction between the other of the electrodes of the first capacitor and the source electrode of the drive transistor; and

5

10

15

35

40

45

50

55

60

24

a second capacitor having electrodes one of which is connected to the other of the electrodes of the first capacitor and the other of which is connected to a second reference potential line which provides a predetermined reference potential,

the driver is configured to:

cause conduction of the first switching transistor through the scanning line in each of all the pixels of the display at a same time to apply the predetermined reference potential to the gate electrode of the drive transistor in the pixel, and thereby stop photon generation of all of the pixels at a same time so that a non-display period is started;

cause conduction of the third switching transistor through the control line in each of all the pixels of the display at a same time to apply a signal voltage held by the first capacitor between the gate electrode and the source electrode of the drive transistor in the pixel, and thereby start photon generation of all of the pixels at a same time so that a display period is started; and drive the display so as to alternate the non-display period and the display period so that the right-eye image and the left-eye image are sequentially displayed,

the non-display period includes a resetting period in which the drive transistor in each of all the pixels of the display is initialized,

the resetting period is:

started by the driver, in each of all the pixels, causing non-conduction of the third switching transistor through the control line and causing conduction of the first switching transistor through the scanning line to apply a constant potential of the second power supply line to the source electrode of the drive transistor through the luminescence element and apply the predetermined reference potential to the gate electrode of the drive transistor, and

terminated by the driver, in each of all the pixels, causing conduction of the third switching transistor through the control line to apply the signal voltage held by the first capacitor between the gate electrode and the source electrode of the drive transistor, the termination being performed after a signal voltage writing period in which, in each of all the pixels, the first capacitor is caused to hold a signal voltage, and

the resetting period has a duration longer than or equal to 20% of a total duration of the display period and the non-display period.

5. The display device according to claim 4, wherein the signal voltage writing period is included in the resetting period, and

in the signal voltage writing period,

the driver is configured to cause, while the third switching transistor in each of all the pixels is non-conductive, conduction of the first switching transistor and conduction of the second switching transistor in each of the pixels in each of the rows through the scanning line provided for the row, and cause the first capacitor in each of the pixels to hold a signal voltage transmitted from the data line provided for one of the columns which includes the pixel, so that the first capacitor of each of all the pixels is caused to hold the signal voltage.
